Des. 179,792
Patented Feb. 26, 1957

179,792

COMBINED LIGHTING FIXTURE AND CLOTHES RAIL

Eben B. Woolley, Milford, Conn., assignor of one-half to Frederic O. Hindle, New Haven, Conn.

Application April 9, 1956, Serial No. 40,972

Term of patent 14 years

(Cl. D33—8)

Fig. 1

Fig. 2

Fig. 4

Fig. 1 is a front perspective view of a combined lighting fixture and clothes rail showing my new design.

Fig. 2 is a front elevational view of the fixture shown in Fig. 1.

Fig. 3 is a top plan view of the fixture.

Fig. 4 is a right end elevational view of the fixture.

I claim:

The ornamental design for a combined lighting fixture and clothes rail, as shown.
